UNITED STATES PATENT OFFICE

146,656

DESIGN FOR AN INKWELL

Rufus W. Hamilton, Jr., and James L. King,
Wilmington, Calif.

Application May 7, 1946, Serial No. 129,404

Term of patent 7 years

(Cl. D74—8)

To all whom it may concern:

We, Rufus W. Hamilton, Jr., and James L. King, residing in Wilmington, in the county of Los Angeles and State of California, have invented a new, original, and ornamental Design for an Inkwell, of which the following is a specification, reference being had to the accompanying drawing, forming a part thereof.

Figure 1 is a side elevation of an inkwell, showing our new design.

Figure 2 is a top plan view thereof.

Figure 3 is a front elevation thereof.

Figure 4 is a perspective view thereof.

We claim:

The ornamental design for an inkwell, substantially as shown.

RUFUS W. HAMILTON, JR.
JAMES L. KING.
